ELASTIC TAPE FOR SLIDE FASTENERS
AND THE LIKEJames A. Hendley, Middletown, Conn., assignor
to The Russell Manufacturing Company, Mid-
dletown, Conn., a corporation

Application January 14, 1935, Serial No. 1,671

2 Claims. (Cl. 139—422)

This invention relates to improvements in woven, knitted, braided, or otherwise fabricated, tapes including weft picks of elastic strands therein, and particularly adapted for the mounting of 5 slide fasteners or the like.

One object of this invention is to provide an improved elastic tape for slide fasteners or the like, which will have elasticity sidewise or transversely of the tape to permit the relief and equalization 10 of excessive strains transversely of the tape.

Another object of this invention is to provide an improved tape for slide fasteners or the like, having weft picks of elastic strands which terminate short of the region where the fastener 15 arms grip the tape, thus avoiding risk of severing elastic strands with consequent injury to the tape.

With the above and other objects in view, this invention includes all improvements over the 20 prior art which are disclosed in this application.

In the accompanying drawing, in which one way of carrying out the invention is shown for 25 illustrative purposes:

Fig. 1 is a fragmental face view of a tape made 25 in accordance with this invention;

Fig. 2 is a sectional view on line 2—2 of Fig. 1; and

Fig. 3 is an enlarged schematic view similar to Fig. 2.

In the description and claims, the various parts 30 are identified by specific names for convenience, but they are intended to be as generic in their application as the prior art will permit.

The tape 10 illustrated in the accompanying 35 drawing consists of a relatively-thin and flexible body or flap 11, substantially plain along one edge 12 and built up at the opposite edge in any improved manner familiar to those skilled in the art to provide a thickened corded or beaded edge 40 13 having, for instance, a longitudinally-extending group of strands 14 incorporated therein.

The tape 10, illustrated in the drawing, consists of two plies of fabric 15 and 16, respectively 45 having warp threads 17 and 18, inelastic weft strands or picks 19 and 20, and elastic weft strands or picks 21 and 22. The strands 14 in the corded or beaded edge 13 may, for example, consist of strands of twisted yarn. The elastic weft picks 21 and 22 may be made of rubber or rubber latex 50 or the like, and may be bare or each may be covered with yarn or thread in any suitable known way.

The elastic weft picks 21 and 22 ordinarily may be made as one continuous weft strand, and in 55 the particular embodiment of the invention illus-

trated in the drawing, this elastic weft strand, comprising the elastic weft picks 21 and 22, will be so woven as to stop short of the region of the tape which is clamped or gripped between opposed arms 23 and 24 of the slide fasteners 25, thus 5 avoiding the risk of the arms 23 and 24 cutting or breaking the elastic weft strand, in event of which cutting or breaking there would be tendency for at least some of the elastic picks of the elastic weft strand to be released from their proper 10 anchorage, with consequent disfigurement of the tape and injury to the effective action thereof.

The elastic weft picks of rubber or the like serve to permit transverse stretching of the tape as, for example, at locations such as indicated in dotted 15 lines at 26, to relieve and equalize excessive strains which may at times be brought on localized areas of the tape, such, for example, as may occur in a jacket when being worn on a person. This relief and equalization of strains thus minimizes 20 the tendency of the slide fasteners to come open or be torn loose from their anchorage on the tape.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended 30 to be embraced therein.

I claim:

1. A multi-ply woven tape designed and adapted for the mounting of slide fasteners along one edge thereof comprising: two plies extending the 35 full width of the tape, said plies being separated along one edge of the tape and the space created filled with stuffing strands to form a thickened edge, and said plies being closely adjacent one another for the remaining width of the tape and 40 forming a relatively-thin flap-like body, all the weft picks of the ply portions forming said thickened edge consisting of inelastic strands, all the weft picks of the ply portions forming a major portion of the width of said flap-like body and 45 which lie within a given ply consisting of elastic strands, said inelastic strands forming weft binder strands extending back and forth from ply to ply along the width of the flap-like body.

2. In combination: a multi-ply woven tape having two plies extending the full width of the tape, said plies being separated along one edge of the tape and the space created filled with stuffing strands to form a thickened edge, and said plies being closely adjacent one another for the re- 55

- maining width of the tape and forming a relatively-thin flap-like body, all the weft picks of the ply portions forming said thickened edge consisting of inelastic strands, all the weft picks of the 5 the ply portions forming a major portion of the width of said flap-like body and which lie within a given ply consisting of elastic strands, said in-

elastic strands forming weft binder strands extending back and forth from ply to ply along the width of the flap-like body; and slide fasteners having opposed arms gripping opposite sides of said tape at said thickened edge. 5

JAMES A. HENDLEY.
